VISCOUS FLUID PUMP

Rudolph D. Maulis, Ravenna, Nebr.

Application August 25, 1934, Serial No. 741,474

1 Claim. (Cl. 103—163)

This invention relates to an improved pump for dispensing heavy oils and fluids, being especially intended for use in connection with conventional oil drums as used at filling stations and the like.

The invention seeks, among other objects, to provide a pump having a disproportionately large inlet opening whereby the pump barrel may rapidly fill with a viscous fluid and wherein said inlet may be manually closed when the pump piston may be operated for discharging the contents of the barrel.

A further object of the invention is to provide a pump wherein both the inlet and the outlet of the barrel will be manually controlled so that the inlet as well as the outlet may be closed at any time to control the flow of fluid into or from the barrel regardless of the position of the pump piston within the barrel.

Still another object of the invention is to provide a pump employing a sleeve valve within the barrel rotatable to control the inlet and the outlet of the barrel and wherein said valve may be rotated manually through the medium of the pump piston.

And the invention seeks, as a still further object, to provide a pump composed of few and simple sturdy parts and which will be adapted for a wide range of use in connection with the handling of viscous fluids.

Other and incidental objects of the invention not specifically mentioned in the foregoing will appear during the course of the following description.

Figure 1 is a vertical horizontal sectional view showing my improved pump installed upon a conventional oil drum, the pump being shown in elevation.

Figure 2 is an enlarged longitudinal sectional view taken medially through the pump, the inlet of the barrel being shown closed and the outlet open.

Figure 3 is a transverse sectional view on the line 3—3 of Figure 2.

Figure 4 is a transverse sectional view on the line 4—4 of Figure 2.

Figure 5 is a transverse section showing the inlet of the barrel open.

Figure 6 is a view partly in section and partly in elevation showing a slight variation of the invention.

In carrying out my invention, I employ a cylindrical pump barrel 10 which is provided at one end with an end wall 11 while at its opposite end 55 the barrel is open and formed in the inner end

portion of the barrel at its upper side is an oblong inlet 12. As will be observed, the barrel is cut away throughout the major portion of its length to provide the inlet 12 and said inlet extends down at the sides of the barrel nearly to a horizontal plane touching the axis of the barrel. In comparison with the length and diameter of the barrel a very large opening is thus provided. Formed in the lower side of the barrel near its outer end is an outlet 13 arranged diametrically opposite the inlet 12. The outlet 13 may be flanged as shown, if so desired, and surrounding the barrel between the inlet and outlet is an externally threaded bushing 14 having a hexagonal or other angular shaped head 15 to receive 10 a wrench.

Rotatably fitting more or less snugly within the barrel 10 is a cylindrical sleeve valve 16 of a length substantially equal to that of the barrel. The valve 16 is open at its inner end while at its 20 outer end said valve is closed by an end wall 17. Formed in the inner end portion of the valve at its lower side is an oblong inlet 18 identical with the inlet 12 of the barrel and formed in the lower side of the valve near its outer end 25 is an outlet 19 identical with the outlet 13 of the barrel. The inlet 18 is adapted to be brought into register with the inlet 12 and similarly, the outlet 19 is adapted to be brought into register with the outlet 13.

Closing the barrel 10 at its outer end is an end cap 20 flanged to fit over the barrel and extending through said flange are screws or other suitable fastening devices 21 securing the cap in position. The cap is provided axially with an 35 annular upstanding bearing-flange 22 and rotatably fitting in said flange is a bushing 23 lipped at its ends for securing the bushing against axial movement.

Slidable through the bushing 23 of the cap 20 40 and through the end wall 17 of the sleeve valve 16 is a squared piston rod 24, the bushing and said end wall being provided with squared openings to snugly receive said rod. Thus, when the rod is turned, the bushing 23 will rotate within 45 the flange 22 of the cap 20 while the sleeve valve 16 will be caused to rotate within the barrel 10. At its outer end the piston rod 24 is bent to provide a handle 25 and detachably fixed to the inner end of the rod is a piston head 26 preferably comprising a suitable leather to coact with the valve 16 and with the barrel 10.

In Figure 1 of the drawing, I have shown my improved pump installed upon a conventional oil drum 27. The drum is provided with the usual 55

head 28 which carries a detachable cover plate 29 secured to the head by bolts 30. Formed in the head near the periphery thereof is the usual internally threaded bung-opening 31 and, as will be observed, the bushing 14 of the pump barrel 10 is screwed into said opening. Thus, the pump may be readily installed upon the drum without the necessity for any structural change therein and as shown, the drum is arranged to lie on its side so that the pump extends horizontally within the bottom portion of the drum, the inlet 12 of the barrel 10 being disposed uppermost.

As will now be seen, the handle 25 of the piston rod 24 of the pump may be manually grasped and turned for rotating the valve 16 to dispose the inlet 18 of said valve in register with the inlet 12 of the barrel 10, as shown in Figure 5, and coincidentally dispose the outlet 19 of the valve out of register with the outlet 13 of the barrel. Accordingly, the outlet of the barrel will be closed while the contents of the drum 27 will, due to the large size of the registering inlets of the valve and barrel, be permitted to rapidly flow into the pump. Thus, the handle 25 may again be turned for rotating the valve 16 to close the inlet 12 of the barrel, as shown in Figures 1, 2 and 4 of the drawing and, as shown in Figures 2 and 3, dispose the outlet 19 of the valve in register with the outlet 13 of the barrel. Accordingly, by manually pulling outwardly on the pump piston, the contents of the pump may, as will be at once appreciated, be discharged at the outlet 13.

I accordingly provide a pump peculiarly adapted for dispensing viscous fluids and in this connection attention is directed to the fact that the piston may be manually rotated at any position of the piston throughout its throw for turning the valve to control the inlet and outlet of the pump. Accordingly, the discharge flow from the pump may be cut off at any instant desired regardless of the position of the pump piston. Furthermore, it is to be noted that as the drum 27 will remain closed by the cover plate 29, the contents of the drum cannot become contaminated with dust and dirt, it being only necessary to provide a small aperture for admitting air to the drum as the fluid is dispensed therefrom.

In Figure 6 of the drawing I have shown a slight variation of the invention wherein I employ a channel shaped attaching ring 32 for the pump. As shown, an aperture is provided in the ring at one side thereof and the pump barrel is inserted through said aperture to extend diametrically of the ring, the barrel being welded or otherwise suitably fixed to the ring. The pump is indicated as a whole at 33 and, as will be observed, the bushing 14 and head 15 as employed in connection with the prior embodiment of the invention are omitted. Otherwise, the

pump 33 is, however, identical with the construction previously described and operates in like manner.

I have shown the ring 32 applied to a conventional drum 34, the head 35 of which is provided with the usual opening 36 and normally closing said opening is a cover plate 37 normally secured to the head by bolts like the bolts 30. As will be observed, the ring 32 is of a diameter to surround the opening 36 in the drum head 35 and, if desired, a gasket 38 may be employed between the ring and said head. The cover plate 37 is arranged to underlie the ring and if preferred a suitable gasket 39 is disposed between said plate and the ring. Extending through the usual bolt openings in the cover plate 37 are bolts 40 screwed into the usual bolt openings in the head 35, the flanges of the ring 32 being apertured to freely accommodate said bolts. Thus, the bolts 40 serve to tightly clamp the ring 32 on the drum head so that the drum 34 may, as shown, be inverted to rest on the ring, when the ring will provide a base for said drum. When the drum is thus inverted, the contents of the drum will, of course, flow by gravity to the pump and it is to be noted that the ring is of such height that the pump lies entirely within the plane of the ring. This variation of the invention thus provides a very effective construction and in employing the ring 32 it is possible, as will be appreciated, to use a proportionately long pump.

Having thus described the invention, I claim:

In a grease pump, a barrel having its inner end permanently closed and provided at its upper side with an elongated inlet extending throughout the major portion of the length of the barrel from a point near the inner end of the barrel to a point adjacent its outer end as well as extending down at the sides of the barrel nearly to a horizontal plane touching the axis of the barrel, the outer end portion of the barrel being provided with an outlet at the lower side of the barrel diametrically opposite the said elongated inlet, a detachable cap closing the barrel at its outer end, a bushing swiveled upon said cap, a sleeve valve rotatable in the barrel and having an inlet and an outlet identical with the inlet and outlet of the barrel displaced relatively and adapted to register alternately therewith, and a piston reciprocable in the barrel and including a square piston rod slidable through said bushing but rotatably supported thereby, said sleeve valve being closed at its outer end and rotatable by said square piston rod for actuating the valve to control the inlet and outlet of the barrel, said bushing having inter-engaging elements cooperating with said cap whereby said cap and bushing only are replaced as a unit.
